ATTORNEY.

UNITED STATES PATENT OFFICE.

SIDNEY SAMPSON, OF DULUTH, MINNESOTA.

ELECTRIC SWITCH.

1,252,498.

Specification of Letters Patent. Patented Jan. 8, 1918.

Application filed January 30, 1917. Serial No. 145,341.

To all whom it may concern:

Be it known that I, SIDNEY SAMPSON, a subject of the King of England, residing at Duluth, in the county of St. Louis and State of Minnesota, have invented certain new and useful Improvements in Electric Switches, of which the following is a specification, reference being had therein to the accompanying drawing.

10 This invention consists of certain improvements in automatic locking and unlocking devices for electric switches and relates particularly to that form of switch known as a disconnecting knife blade 15 switch.

As is well known in the art, disconnecting switches are frequently, if not in the majority of cases, located remotely from convenient direct manual operation and are 20 usually opened and closed by a pole in the hands of the operator, having a hook in the end thereof for engagement with the switch blade or within a suitable hole, formed for the purpose, through the free end of the 25 blade.

The object of my present invention is to provide a simple and inexpensive automatic locking and unlocking device for the type of switch above referred to.

30 In the accompanying drawings forming part of this application and in which like reference characters indicate like parts:

Figure 1 is a side elevation of my improved form of switch attachment, and

35 Fig. 2 is an enlarged cross sectional view taken on the line A—B, Fig. 1.

I have illustrated the switch to which my invention is applied as being mounted upon a suitable base 1 and comprising the two 40 extended bifurcated contacts 2 and 3 and the blade member 4, which is pivotally supported as at 5 intermediate the bifurcated members 6—6 of the contact 2 and the opposite free end swingingly adjustable to or 45 from the contact 3, and frictionally engaged intermediate the bifurcated terminals 7—7 thereof when closed, as is common in such switches.

The contacts 2 and 3 extend through the 50 base 1 and are connected with the circuit wires in any desired manner.

While I have shown this particular form of switch having a base in connection therewith, it is understood that in many cases 55 such a base is not at all necessary and that the blade 4 may be mounted within the

contacts without such base, provided the former are suitably rigidly fixed.

As a means for locking the blade 4 in place between the terminals 7—7 of the 60 contact 3, there is fixed, in any desired manner, as by a suitable through rivet 15 or by soldering, if preferred, to the outer side wall of each member 7, a metal spring member 8, said fixed connection being adjacent 65 the base of the contact.

The spring members 8—8 are bent at right angles over the ends of the terminals 7 toward each other forming opposed shoulders 9—9 which coöperate with each other 70 in forming an adequate abutment for preventing the accidental withdrawal of the free end of the blade.

From the inner adjacent corners of the shoulders each member is again bent at substantially right angles, though in the opposite direction to that of the previous end, and flared gracefully outwardly from each other to form an easy entrance for the blade when forced therebetween and which action 80 springs the members 8—8 sufficiently apart to allow the blade to fully enter between the terminals and become locked therein by the members 8 assuming their normal position with the shoulders 9—9 adjacent each other 85 beneath the blade.

For operating the blade and automatically unlocking the same when being opened, there is pivotally mounted upon the free end of the blade as at 10, a rockable manipulating 90 member 11 having a hole 12 therethrough for engagement by the hook in the pole commonly used for such purposes, and whereby the free end of the blade is raised or lowered, 95 as desired.

The lower inner portion of the manipulating member is extended downwardly somewhat and then turned at substantially right angles, the terminus extending normally parallel with the switch blade, being increased in thickness near its extreme end, as at 13, and then formed in inverted V-shape transversely, with the apex thereof normally ready to enter between the flaring ends of the spring members 8—8 and separate them 100 during the process of unlocking the switch. In forming the manipulating member 11, it is desirable to have that portion extending inwardly parallel with the blade of a weight sufficient to more than counteract the weight 110 of that portion upon the opposite side of the pivotal point of suspension 10 so that the

2
manipulating member normally remains in the position illustrated in Fig. 1.

The operation of the device is as follows: Assuming the switch to be placed overhead 5 against a ceiling and open, and which may be reached with a pole, the hook in the pole is engaged within the hole 12 of the manipulating member 11 and the blade swung upwardly toward the contact 3 and forcibly 10 thrust in between the terminals 7—7 thereof, it having sprung the locking members 8—8 apart during such entrance.

The members 8—8 will, upon passage of 15 the blade therebetween, assume their normal position with their angular shoulders 9—9 adjacent each other beneath the blade thus effectually locking it in such closed position. The face of the manipulating member 11 above the pivotal point 10 abuts the end of 20 the blade 4 and prevents the member 11 from rising above a point parallel with the blade, as is obvious.

When it is desired to open the switch, a 25 downward pull of the hook in the hole 12 will by the rocking action of the member 11 thrust the head 13 thereof upward intermediate the flared ends of the spring members 8—8 and separate them sufficient to admit the free passage outward of the blade 4 and 30 which operation will bring the head 13 in direct engagement with the lower edge of the blade, thus retarding further movement of the member in respect to the blade.

A further pull downward will freely with- 35 draw the blade from engagement with the contact and result in an effectual and simple opening of the switch and that with but a single stroke of the operating pole.

While I have illustrated the locking 40 spring members 8—8 as being attached directly to the sides of the contact 3, it is evident that the same may be upon an independent mounting either in front of or in the rear of the contact, as desired, without 45 departing from the spirit of the invention.

Having thus described my invention, what I claim and desire to secure by Letters Patent, is:

1. A locking and unlocking device for 50 electric switches, comprising two opposed coöperating members for normally retaining the switch in locked position, and means pivotally carried by the free end of the switch

and engageable intermediate of the coöperating members whereby the switch may be 55 closed or opened by a single movement of the operating rod when engaged with the last mentioned means.

2. In an electric knife blade switch, the combination of two contact members, a 60 switch blade pivotally carried by one of said members, and engageable with the other of said members, opposed separable locking members carried upon opposite sides of the last mentioned contact member and means 65 pivotally carried by the switch blade for separating the locking members when the switch is being unlocked.

3. In an electric knife blade switch, the combination of two contact members, a 70 switch blade pivotally carried by one of said members and engageable with the other of said members, opposed separable resilient locking members carried upon opposite sides of the last mentioned contact member and 75 overlapping the end of same, a manipulating member pivotally carried upon the extreme free end of the switch blade, said manipulating member having a wedge shaped projecting head for separating the locking 80 members and means for operating the manipulating member simultaneously with the opening and closing of the switch.

4. The combination with a knife blade switch of the character described, designed 85 to operate within a bifurcated contact member, of opposed resilient locking members carried upon either side of the bifurcated contact member, the extreme free ends of the locking members diverging outwardly, a 90 manipulating member pivotally supported upon the extreme free end of the blade of the switch, a projection of the manipulating member having a wedge shaped head for engagement intermediate of the diverging ends 95 of the locking members and means whereby the manipulating member is operated simultaneously with the opening and closing of the switch.

In testimony whereof I hereunto affix my 100 signature in the presence of two witnesses.

SIDNEY SAMPSON.
